David P. Chuboff, North Barrington, and Kendrick T. Parsell, Chicago, Ill., assignors to Zenith Radio Corporation, Chicago, Ill., a corporation of Delaware

Filed July 2, 1969, Ser. No. 18,026

Term of patent 14 years

Int. Cl. D14—03

U.S. Cl. D56—4

FIG. 4

FIG. 3

FIG. 1 is a left side, top and front perspective view of a stereo radio-phonograph, showing our new design;

FIG. 2 is a left side elevational view, the right side being substantially a mirror image thereof;

FIG. 3 is a front elevational view, the rear being substantially a mirror image thereof; and

FIG. 4 is a top plan view thereof.

A portion of FIG. 1 is diagonally lined to indicate transparency, and portions of the drawing figures are shaded to indicate contrast in appearance.

We claim:

The ornamental design for a stereo radio-phonograph, substantially as shown and described.
